Merchant and Flegore

UNITED STATES PATENT OFFICE.

EMMA NELSON, OF MINNEAPOLIS, MINNESOTA.

MATTRESS CARRIER.

Application filed November 2 1927. Serial No. 230,485.

My invention has for its object to provide a simple and highly efficient mattress carrier, and to this end it consists of the novel devices and combinations of devices herein-
5 after described and defined in the claims.

My improved mattress carrier, after a mattress has been rolled to a relatively compact form, may be readily applied thereto and secured to hold the mattress rolled so
10 that the same may be easily carried by a single person.

In the accompanying drawings which illustrate the invention, like characters indicate like parts throughout the several views.

15 Referring to the drawings:

Fig. 1 is a perspective view of the mattress carrier in an open position;

Fig. 2 is a fragmentary detail view showing the latch connecting the outer bars;

20 Fig. 3 is a detail view with some parts sectioned on the line 3—3 of Fig. 2; and

Fig. 4 is a view in end elevation showing the mattress carrier applied to a rolled mattress, indicated by broken lines, some parts
25 of the mattress carrier being diagrammatically illustrated in part by broken lines.

The mattress carrier comprises two laterally spaced outer bars 5 and 6, each of which is connected by end and intermediate coiled
30 springs 7 to an intermediate bar 8. The bars 5—6 and 8 are preferably made from relatively long pieces of wood that are rectangular in cross section and the springs 7 are attached thereto by screw eyes 9.

35 A handle 10 is attached to each bar 5—6 at its intermediate portion and a handle 11 is attached to the intermediate bar 8 at its intermediate portion. To connect and hold the two outer bars 5—6 when the mattress carrier is applied around a rolled mattress, there is provided a main-channel-shaped
40 latch 12 pivoted to the bar 5 and adapted to be turned into a position to receive the two bars 5—6 when assembled, as shown in Figs.
45 2 and 3, to hold the same against lateral sepa-

ration. A latch plate 13 is pivoted to the main latch 12 and arranged to be turned under the bars 5—6 and hold the same in the main latch 12.

To apply the mattress carrier to a mat-
50 tress A, said mattress is rolled, as indicated by broken lines in Fig. 4, and the mattress carrier placed therearound and the two bars 5 and 6 moved together by stretching the springs 7. The latch 12 is then turned into a position to receive the bars 5 and 6 and the latch plate 13 turned thereunder to hold the bars 5—6 in the main latch 12. Obviously,
55 the springs 12 will stretch to cause the mat-
tress carrier to fit mattresses that vary mate-
rially in diameter.

When the mattress carrier is applied to a mattress, as shown in Fig. 4, the mattress may be easily carried by the two handles 10 or by the handle 11, or the mattress can be
60 carried between two persons, one taking the handles 10 and the other the handle 11.

During the time the mattress holder is applied to a mattress, the mattress will remain
65 rolled in compact form so that the same may
70 be easily handled.

What I claim is:

1. A mattress carrier comprising a pair
of outer bars, an intermediate bar, coiled
springs connecting the outer bars to the in-
75 termediate bars, and a latch for separably
connecting the outer bars.

2. A mattress carrier comprising a pair
of outer bars, an intermediate bar, coiled
springs connecting the outer bars to the in-
80 termediate bar; a channel-shaped main latch
pivoted to one of the outer bars and adapted
to be turned into a position to receive the
two outer bars and hold the same against
85 lateral separation, and a latch plate pivoted
to the main latch and arranged, when closed,
to hold the outer bars in the main latch.

In testimony whereof I affix my signature.

EMMA NELSON.
